UNITED STATES PATENT OFFICE

2,476,328

OPERATING SPRING RETAINER FOR FIREARMS

Clarence E. Simpson, Springfield, Mass., assignor to the United States of America as represented by the Secretary of War

Application November 8, 1948, Serial No. 59,002

2 Claims. (Cl. 89—199)

(Granted under the act of March 3, 1883, as amended April 30, 1928; 370 O. G. 757)

1

The invention described herein may be manufactured and used by or for the Government for governmental purposes without the payment to me of any royalty thereon.

This invention relates to a device for retaining the operating spring of a firearm within the housing or cylinder containing such spring.

The present invention is concerned with a device for retaining the spring for an operating rod of a firearm within the cylinder or housing in which such operating rod functions. Numerous devices to retain a spring in a cylinder of a firearm have been resorted to which have proven to be far from satisfactory. Furthermore such retaining devices were awkward to remove, making disassembly of the operating rod and accompanying spring slow and difficult.

Accordingly it is an object of this invention to provide a device for positively retaining an operating rod spring within a cooperating element of a firearm.

Another object of this invention is to provide a device for retaining an operating rod spring in a firearm which is readily releasable for quick and easy removal of the operating rod and spring.

The specific nature of the invention as well as other objects and advantages thereof will clearly appear from a description of a preferred embodiment as shown in the accompanying drawings in which:

Fig. 1 is a fragmentary longitudinal sectional view of a firearm showing an operating rod spring secured within the cylinder by means of the securing device of this invention.

Fig. 2 is a sectionalized view taken on line 2—2 of Fig. 1.

Fig. 3 is a perspective view of the spring guide assembled to the retainer.

In Fig. 1 there is shown a fragmentary sectional view of a firearm receiver 10, a barrel 11 is secured to the receiver, a rectangular housing 12 is disposed underneath barrel 11 and an operating slide 13 is slidably mounted in housing 12 and receiver 10 for reciprocal movement. An operating rod 23 is connected to slide 13. The rear portion of operating rod 23 shown in Fig. 1 is hollow and there is inserted in such hollow portion an operating rod spring 14. The end of spring 14 within rod 23 seats against the bottom of the hollow portion of such rod. Inasmuch as this invention relates primarily to the means for retaining the operating rod spring within the housing, further description of the firearm is not necessary.

The other end of spring 14 surrounds a spring guide 15 and abuts a plate member 16 integrally

5 formed or otherwise secured to the end of guide 15. On the rear face of plate 16 there is provided a lug 17 having a rounded end 18. A retainer 19 is pivotally secured to plate 16, a bifurcated arcuate lug 20 being provided thereon to surround lug 17 for such pivotal mounting. A pin 21 rotatably secures such members. One end of retainer 19 is engageable with a notch 22 provided in the bottom of receiver 10 as shown in Fig. 1 whereby operating spring 14 and spring guide 15 are retained within housing 12.

In the position shown in Fig. 1, retainer 19 secures such spring and guide rod to the firearm. When, however, a forward force is exerted 15 against retainer 19 to disengage the bottom end of such retainer from the rear shoulder of notch 22, retainer 19 may be pivoted forwardly out of engagement with notch 22 and thus spring 14 and spring guide 15 may be readily removed from 20 the firearm through the receiver thereof. Assembly of such retainer to the receiver is accomplished by a reversal of the procedure just described, namely, the spring and spring guide and retainer are pushed forwardly and released when 25 retainer 19 is over notch 22 whereby the rearward bias of spring 14 pivots retainer 19 into notch 22 thereby securing the rear end of the spring and spring guide.

Thus it is seen from the above description that 30 there is here provided a device which positively retains the operating spring and guide rod to the firearm. Quick release of such members is readily obtainable with this device which facilitates and speeds up disassembly of the firearm. While 35 there has been described herein only one specific application of this invention, such securing device may of course be utilized where any other similar arrangements of retaining a spring may be encountered.

40 I claim:

1. In a firearm having a receiver, a barrel horizontally secured to the receiver, a housing secured to the receiver and disposed parallel to the barrel, an operating slide adapted for reciprocal movement in the receiver and housing, and a hollow operating rod connected to the operating slide, the improvement comprising a rod-like spring guide in the housing, a plate member secured to the end of said spring guide, an operating spring surrounding said spring guide, one end of said spring abutting said plate member and the other end contained in the operating rod, and a retainer pivotally secured to said plate member, said retainer engageable with the receiver and the housing to removably secure said

spring guide in the housing against the bias of said operating spring.

2. In a firearm having a receiver and a notch in the receiver, a barrel horizontally secured to the receiver, a housing secured to the receiver and disposed parallel to the barrel, an operating slide adapted for reciprocal movement in the receiver and housing, and a hollow operating rod connected to the operating slide, the improvement comprising a rod-like spring guide in the housing, a plate member secured to the end of said spring guide and adapted for slidable movement in the housing, said plate member having a lug thereon, a retainer member pivotally secured to said lug, and an operating spring in the operating

15

rod, said spring arranged to surround said spring guide and abut said plate member, one end of said retainer member being engageable with the notch in the receiver and the opposite end thereof engageable with the wall of the housing to secure said spring guide against the bias of said operating spring, said pivotal mounting of said retainer permitting forward pivotal movement of said retainer against the bias of said operating spring whereby said retainer is disengaged from the notch for removal of said spring guide and spring from the housing.

CLARENCE E. SIMPSON.
